United States Patent Office.

THOMAS STEWART, OF PHILADELPHIA, PENNSYLVANIA, ASSIGNOR
TO HIMSELF AND WILLIAM C. STILES, OF SAME PLACE.

Letters Patent No. 90,405, dated May 25, 1869.

IMPROVEMENT IN FILTERS.

The Schedule referred to in these Letters Patent and making part of the same.

To all whom it may concern:

Be it known that I, THOMAS STEWART, of the city of Philadelphia, in the State of Pennsylvania, have invented a new and useful Apparatus for Filtering Petroleum and Lubricating and other Oils; and I do hereby declare that the following is a full, clear, and exact description of the construction and operation of the same, reference being had to the accompanying drawings, making a part of this specification, in which—

Figure 1 is a central vertical longitudinal section of the said apparatus, and

Figure 2, a horizontal section of the same below the dotted line *x w* of fig. 1.

Like letters of reference indicate the same parts when in both figures.

The crude petroleum and other similar hydrocarbon-liquids contain, besides water, a peculiar, thick, sedimentary substance, and often fine sand or grit, all of which require to be removed when the liquid is intended to be used as a lubricant; and

The object of my apparatus is to effect the removal of the same in a more simple, rapid, and practical manner than heretofore.

The nature of my invention consists in the construction and combined arrangement of devices hereinafter described, whereby the said sedimentary and other impurities of the crude liquid are arrested during its passage through the apparatus, and the purified hydrocarbon-liquid discharged therefrom by gravitation, leaving the said impurities, which can afterward be removed with facility from the apparatus, as occasion may from time to time require.

Referring to the drawings—

A B is a closed chamber, of wood, or other suitable material, in which is contained the principal portion of an apparatus, consisting of two sheet-metal cylinders, C and D, supported upon and communicating with each other through a sheet-metal chamber, E, the cylinder C being provided with a detachable strainer, F, the cylinder D with a removable or changeable stratum of granulated charcoal, G, or its equivalent, secured between two detachable perforated diaphragms, or foraminous plates, H H', and an outlet tube, I, and the chamber E with an outlet tube, *e*, which is intended to be fitted with any suitable stop-cock, not shown in the drawings.

The cylinder C projects upward vertically through the top of the chamber A B, is open at the top, and is about three feet in diameter, and twenty feet high from the top of the chamber E, and into this chamber E it opens, through a perforated diaphragm, *c*.

The strainer F consists of three or more layers of loose felt, *f*, or its equivalent, secured between a skeleton-frame of wire, *f'*, below, and a rim, *f''*, of sheet-metal, above, and resting upon the diaphragm *c*, in the lower part of the cylinder C, the frame *f'* and rim *f''* being attached to a rod, or stem, *f'*, the upper end of which projects out above the mouth of the said cylin-

der, and serves as a ready means of withdrawing and replacing the strainer F. (See fig. 1.)

The cylinder D is also about three feet in diameter, but is only about half the height of the cylinder C, and, like the latter, its lower end rests upon and opens into the chamber E.

It has about one-third of its length occupied by a mass of granulated charcoal, clean sand, or other suitable filtering or purifying-substance, secured in a readily removable or changeable manner, at about midway between its ends, by means of the two diaphragms H H', with a layer of any suitable straining-cloth between the said charcoal and each of the diaphragms.

The outlet-tube I extends from the space which is immediately above the upper diaphragm, horizontally outward through the external case A B.

The chamber E has a bottom, *e*', which slopes downward from each end of the same nearly to its middle, at which latter part the outlet-tube *e* projects through the sides of the same, and the case, or outer chamber A B, and is intended to have a stop-cock attached to it on the outer side of the chamber A B.

Operation.

The liquid to be strained is to be steadily run into the cylinder C, and kept at about the height of the faint line *x* therein, (see fig. 1,) while, in consequence of the head thus kept up, the liquid is rapidly filtered down, through the layers of the fabric *f*, into the chamber E, and thence upward through the filtering or fining-substance, G, which is confined between the two perforated diaphragms, H H', and thence, in a condition free from all the sedimentary and other objectionable impurities, out through the tube I, to any suitable reservoir.

The water sinks to the bottom of the chamber E, and floats the oil thereon, while the grit and other sedimentary matter are separated by the strainer F and filter G, all of which can be removed with facility when necessary.

In cold weather, steam is intended to be run through the outside containing chamber A B, for the purpose of keeping the crude liquid as thin as possible.

I wish it to be understood that I do not intend to confine this apparatus to the particular dimensions or materials of construction stated herein; but, having fully described my invention,

What I claim, and desire to secure by Letters Patent, is—

The cylinder C, with its detachable strainer F, the cylinder D, with its detachable or changeable filtering-medium G, and outlet-tube I, and the intermediate chamber E, with its outlet-tube *e*', the said parts being combined together and arranged within a suitable chamber, at B, so as to operate substantially in the manner described, for the purpose specified.
